UNITED STATES PATENT OFFICE.

JULIUS HILDER, OF NEW YORK, N. Y.

BELT.

SPECIFICATION forming part of Letters Patent No. 661,695, dated November 13, 1900.

Application filed June 11, 1900. Serial No. 19,845. (No model.)

To all whom it may concern:

Be it known that I, JULIUS HILDER, a citizen of the United States, residing in New York city, borough of Manhattan, State of New York, have invented certain new and useful Improvements in Belts, of which the following is a specification.

My invention relates more particularly to improvements in waist-belts; and it has for its object to provide improved means for connecting the ends of straps, ribbons, or the like; and to this end the invention consists in an attachment or frame provided with bars, loops, or the like extending lengthwise of the frame and at opposite sides of the central portion of the same and to which the belt straps, ribbons, or the like are to be attached, so that they may extend from the frame in opposite directions.

20 The invention also consists in the novel details of improvement, that will be more fully hereinafter set forth and then pointed out in the claims.

Reference is to be had to the accompanying drawings, forming part hereof, wherein—

25 Figure 1 is a face view of a belt embodying my invention, the straps being partly broken away. Fig. 2 is a rear view of the same, the straps on one side being removed. Fig. 3 is an edge view of the frame looking from the right in Fig. 2. Fig. 4 is a rear face view of part of a frame, illustrating a modified construction of the same; and Fig. 5 is a rear view of a portion of a belt provided with a modified form of frame.

30 Similar letters of reference indicate corresponding parts in the several views.

In the accompanying drawings the letter A indicates generally a frame, to which straps, 40 ribbons, or the like B are to be connected. In Figs. 1 to 4, inclusive, the frame A is shown composed of two members A' A², disposed transversely of the belt, and thereby arranged to extend vertically when the belt is placed 45 around a waist, and in said figures the members A' A² are shown movably connected, as by a hinge C or other movable connection, the parts of which may be secured to the members of the frame by solder or in any other 50 suitable manner. The members of the frame may be made in any suitable form—as, for instance, in sheet metal, as in Figs. 1, 2,

and 3, which may have any suitable configuration or embellishment—or the members of the frame may be composed of longitudinally-disposed wires or bars a, connected by cross-wires a', to which suitable ornaments a² may be attached, as in Fig. 4. The members of the frame are each provided with one or more longitudinally-disposed strap-holders, 55 shown in the form of bars or loops D, which are located at such a distance from the main body of the frame that the straps, ribbons, or the like B may be folded around them and secured by stitches b or in other suitable manner, whereby the straps are attached to the frame. The bars or loops D may be in the form of wires having their ends bent toward the frame and secured thereto by solder or otherwise, and these bars or loops are secured on opposite sides of the central line of 60 the frame, so that the straps B may extend in opposite directions from the frame to be passed around a waist. Said straps may be provided at their outer ends with any suitable or well-known means for connecting them together. By having the bars or loops 65 D on the inner face of the frame the ends of the straps that connect with the bars are concealed by the frame when the belt is in position around a waist, and the frame thereby affords an ornamental central attachment for connecting the ends of the oppositely-extending straps together. By having the two members A' A² of the frame hinged or pivoted together 70 the frame can bend to conform to the curve of a waist and lie snugly against the same; also, when the members of the frame are hinged or pivoted together as shown the straps B when connected together around a 75 waist keep the members of the frame spread apart, as indicated in Fig. 1, and the frame when arranged as shown produces a bodice-like effect at the back portion of the belt. The loops or bars D on each side or member 80 of the frame enable two or more straps B to extend side by side, and said bars or loops may be curved or arch-like, their concave edges facing outwardly or laterally, whereby when two or more straps B are attached to 85 each side of the frame they may converge toward the end fastenings, thereby overlapping and producing a tapering effect in the straps 90 from the centrally-disposed frame A toward 95 each other. The straps B may be made of any suitable material, such as leather, cloth, or 100 other flexible material, and may be of any suitable width or thickness.

opposite ends of the belt, as will be understood from the drawings.

While in Figs. 1 to 4 I have shown the frame A comprising two members hinged together, 5 it is evident that the frame may be in a single piece of material, as indicated in Fig. 5, and provided at opposite sides of the central vertical line with the loops or bars D, arranged to receive the folded ends of the straps B, as 10 before described. In either case as the bars or loops D are located at opposite sides of the vertical center of the frame A separate straps may be attached to each, so as to project from the frame in opposite directions, and thereby 15 the straps can be readily replaced when desired. By having each bar or loop D of a length approximating the width of a strap B the latter will be maintained in position from sliding along the frame transversely of the 20 belt, and this will be found advantageous where the straps converge to a common point, as will be apparent. A single bar or loop D may be used on each side of the frame; but I prefer to use two or more bars in substantial 25 alignment lengthwise of the frame. Fig. 3 shows the frame A curved so as to conform somewhat to the vertical curvature of a wearer's back.

Having now described my invention, what 30 I claim is—

1. A belt frame or attachment having strap-holders located on opposite sides and extend-

ing laterally in opposite directions and adapted to be attached to straps or the like, substantially as described.

2. A belt frame or attachment having a plurality of strap-holders on each side extending in substantial endwise alignment each holder being adapted to have a strap attached to it to retain the straps from lateral displacement, 40 substantially as described.

3. A belt frame or attachment comprising two members located side by side and movably connected together, each member having a strap-holder that diverges laterally and is 45 adapted to receive a strap or the like, substantially as described.

4. A belt comprising a frame provided with strap-holders on opposite sides, and pairs of straps attached to the strap-holders, the straps 50 of each pair converging outwardly, substantially as described.

5. A belt comprising a frame provided with strap-holders located on opposite sides, the strap-holders diverging laterally from the central portion of the frame, and a plurality of straps connected to the holders on opposite sides of the frame, a pair of straps on each side converging outwardly and overlapping, 55 substantially as described.

JULIUS HILDER.
